UNITED STATES PATENT OFFICE.

MATTHEW HENRY PHINEAS RIAILL SANKEY, OF BILTON, NEAR RUGBY, ENGLAND.

STEAM-TURBINE.

No. 874,443.

Specification of Letters Patent.

Patented Dec. 24, 1907.

Application filed September 20, 1905. Serial No. 279,273.

To all whom it may concern:

Be it known that I, MATTHEW HENRY PHINEAS RIAILL SANKEY, late captain R. E., a subject of the King of Great Britain and 5 Ireland, and residing at Bawnmore, Bilton, near Rugby, England, have invented certain new and useful Improvements in and Relating to Steam-Turbines, of which the following is a specification.

10 My invention relates to steam turbines, and has for its object to produce a type of steam turbine which shall be more economical and of simpler construction than those at present in use.

15 The invention also consists in a method of fixing the blades on steam turbine wheels.

By means of my invention the total number of rows of blades required in a turbine of given power is greatly reduced.

20 Referring now to the accompanying drawings:—Figures 1 and 2 show cross section and elevation of a portion of bladed strip showing a method of blade fixing. Figs. 3 and 4 are sections on the lines A A and B B 25 respectively of Fig. 1, the latter section showing the bladed strip removed from the drum groove. Fig. 5 is a cross section of the strip on the lines C C of Fig. 2. Figs. 6 and 7 are back and front perspective views of the blade 30 shown in Figs. 1 and 2. Fig. 8 is a cross sectional view of a portion of the rotary and fixed members, showing the contour of the root of the blades in elevation, and the calking and holding strips in cross section. Fig. 35 9 is a cross sectional view of a blade of more substantial cross section showing the stamped portion of the root of the blade in plan.

The invention concerns more particularly the construction of the blades and the manner in which these blades are attached to the 40 turbine.

One manner of attaching the blades to the turbine, when somewhat thin blades are used, consists in forming grooves *g* (Fig. 2) 45 in the rotating drum, and the casing, in the respective positions to be occupied by the rows of blades, *b* and *c*, the grooves *g* being undercut. A foundation ring *h*, the cross section of which conforms to the undercut, 50 but which has a smaller section than the groove to allow for a calking strip *i*, is bent into a semi-circle and radial notches *j* are cut into it, extending from about one-third to one-half of the thickness of the ring *h*. 55 For the fixed blading these notches *j* would be on the concave side of the ring and for

the moving blade on the convex side. The notches are parallel to the axis of the turbine when the rings are in position, and the pitch is so regulated as to give the proper 60 pitch to the blades. The root end of each of the blades, *b* and *c*, is stamped into a special shape, the central part *k* of the end being flattened to conform to the notch *j* in the foundation ring *h*, both as to width and 65 depth, and the two sides *l* being bent back at right angles to the central part, and splayed outwards to the same angle as the bevel on the foundation ring *h*. These sides *l* are made longer than the center part *k*, so as to 70 extend nearly to the underside of the foundation ring *h*, when in position, as shown in Fig. 1. To fix the blades into the rotating drum, or into the casing, the individual blades are pushed, into the notches *j*, in the 75 foundation ring *h*, thus forming a semi-circular ring of radiating blades. The ring *h* is placed in the groove *g* in the drum or casing, and short pieces of calking strip *i* are pushed into the space remaining, and are 80 calked in.

Where the blades are of the much more usual thick section shown in Fig. 9, I prefer to stamp the root ends so that there shall be less displacement of the metal of the blade 85 towards the flanges, the edges of the blade at the root being bent inwards so that the total width at the root is considerably less than that at the upper or working part of it. The blade root is inserted in slots in the root 90 strips as before, these slots however being a little wider to correspond with the thicker flat part of the root; but as the root portion is narrower than the upper portion, as seen in Fig. 8, there is sometimes a little difficulty 95 in putting in a single calking strip, as used in the form shown in Fig. 1, on account of the overhang of the side of the blade. To overcome this difficulty I provide adjacent to the root strip an auxiliary or dummy strip *s*, 100 preferably in two or more sections, and between this strip *s* and the side of the dovetailed groove I insert the calking strip *i*, as used in the other case. The strips are then well calked in, and a very secure blade 105 fastening is obtained. The blades may if desired be provided with a shroud ring, as shown at *t*, in Fig. 8. It will be seen that by these constructions not only the foundation ring, but each individual blade, is securely dovetailed into the drum or casing.

Having now described my invention what

I claim as new and desire to secure by Letters Patent is:—

1. In an elastic fluid turbine the combination of a blade carrying member having an annular dovetailed groove formed therein, a strip in the groove, transverse cuts on the outer face of said strip extending from side to side, blades inserted within the cuts of the strip, side portions on the blades straddled over the strip and means for holding the blades in place.
2. In an elastic fluid turbine, the combination of a blade carrying member having a dovetailed groove therein, a dovetailed ring in such groove having transverse grooves or cuts therein, blades each having a central portion adapted to fit into such transverse grooves or cuts, extending side portions projecting into the annular groove between the ring and the carrying member and a calking ring for securing the blades in position.
3. In combination in an elastic fluid turbine, blade carrying strips having cross grooves cut in the outer faces part way through the strips, blades in the strips, each of which blades is stamped at the root end so that its middle portion is flattened to conform to the groove in the strip, into which it is set, while the two sides are longer than the central part, and are bent back at right angles to the middle so as to embrace the strip, grooves in the drum and casing into which the strips are inserted, and means

whereby the blades are held firmly in the strips, and the strips are held in the grooves. 35

4. In combination in an elastic fluid turbine, blade carrying strips having cross grooves cut in the outer faces part way through the strips, blades in the strips, each of which blades is stamped at the root end so 40 that its middle portion is flattened to conform to the groove in the strip, into which it is set, while the two sides are longer than the central part, and are bent back at right angles to the middle so as to embrace the 45 strip, grooves in the drum and casing into which the strips are inserted, and a calking lug and a dummy lug whereby the blades are held firmly in the strips, and the strips are firmly in the grooves. 50

5. A turbine blade formed with a single plate of pressed metal having its root end bent into three planes, the outer two of which are at substantially right angles to the third and extend beyond the end thereof and that 55 of an acute angle to each other, forming thereby a dovetailed projection by which the blade is secured to the turbine blade carrying member.

In testimony whereof I have signed my 60 name to this specification in the presence of two subscribing witnesses.

MATTHEW HENRY PHINEAS RIALL SANKEY.
